UNITED STATES PATENT OFFICE.

LOUIS H. TREIBER, OF DANBURY, IOWA.

AUTOMATIC FEED-CARRIER.

1,208,700.

Specification of Letters Patent. Patented Dec. 12, 1916.

Application filed March 21, 1916. Serial No. 85,648.

To all whom it may concern:

Be it known that I, LOUIS H. TREIBER, citizen of the United States, residing at Danbury, in the county of Woodbury and 5 State of Iowa, have invented certain new and useful Improvements in Automatic Feed-Carriers; and I do hereby declare the following to be a full, clear, and exact description of the invention, such as will enable others skilled in the art to which it 10 pertains to make and use the same.

The invention relates to improvements in carriers or conveyers.

The object of the present invention is to 15 improve the construction of carriers or conveyers and to provide a simple, practical and efficient carrier designed for handling feed and adapted to save time and labor and money in delivering the same to the stock to be fed and capable of enabling the operator 20 to manipulate it from a given point without moving away from the same and of conveying a quantity of food or other material to the desired point and of discharging the 25 same.

A further object of the invention is to provide a feed carrier of this character adapted to be adjusted for enabling the contents to be uniformly distributed over a 30 given area so as to distribute the feed instead of dumping the same at one point.

It is also an object of the invention to provide a carrier adapted for feed, fertilizer or the like and capable of control by a single 35 operated rope for actuating the bucket or receptacle to move the same to the desired point and also for tripping the receptacle to discharge its contents and for returning the receptacle to the starting point.

40 With these and other objects in view the invention consists in the construction and novel combination and arrangement of parts hereinafter fully described, illustrated in the accompanying drawings and pointed out in 45 the claims hereto appended, it being understood that various changes in the form, proportion and minor details of construction may be resorted to without departing from the spirit or sacrificing any of the advantages of the invention.

50 In the drawings Figure 1 is a side elevation of a carrier or conveyer constructed in accordance with this invention, Fig. 2 is an end elevation of the same, Fig. 3 is an enlarged side elevation of the bucket or recep-

tacle, showing the same in its closed position, Fig. 4 is a transverse sectional view of the same, Fig. 5 is a side elevation on a reduced scale showing the dumping bottom section open, Fig. 6 is an enlarged vertical sectional view of one end of the receptacle illustrating the construction of the mechanism, Fig. 7 is a detail perspective view of a portion of the supporting bar or member, Fig. 8 is a detail perspective view of one of the carriers, Fig. 9 is a horizontal sectional view on the line 9—9 of Fig. 6.

Like numerals of reference designate corresponding parts in the several figures of the drawings.

In the accompanying drawings in which is illustrated the preferred embodiment of the invention, the carrier or conveyer which is designed for handling all kinds of feed as well as fertilizer and various other material 5 in bulk comprises in its construction a bucket or receptacle 1 preferably of rectangular form composed of sheet metal sides 2, ends 3, and hinged bottom sections 4. The sides and ends are reinforced at their marginal 10 edges by angle strips 5 and the dumping bottom sections 4 which are connected at their outer ends to the lower edges of the end walls 3 of the receptacle by hinges 6 meet at the center of the receptacle when closed and are provided with sides or wings 7 which fit against the side walls 2 of the bucket or receptacle when the latter is closed. The dumping bottom sections with their 15 sides or wings 7 are adapted to form chutes 8 for enabling the contents of the receptacle to be spread over the surface of the ground instead of being discharged at one point when desired.

The bucket or receptacle is provided at its 20 end portions with hangers constructed of suitable metal and composed of an upper bar or member 9 and lower laterally diverging arms 10 preferably consisting of separate pieces and secured at their upper terminals 11 to the opposite faces of the upper bar or section 9. The upper bar or section is bent to form an approximately hook-shaped upper portion 12 and to arrange its lower attached portion centrally of the upper hook-shaped portion. The upper hook-shaped portion receives a wheel 13 having a grooved periphery and adapted to run on a track 14 which may consist of a wire cable, rope or any other suitable means and which ex- 25 30 35 40 45 50 55 60 65 70 75 80 85 90 95 100 105 110

tends between anchoring posts 15 and 16 or other suitable support. One of the posts or supports is provided with a tension device 17 to enable the track to be stretched to the 5 desired tension. The hangers are preferably connected by a longitudinal bracing bar or member 18 extending over the receptacle or bucket and secured between the upper portions of the diverging arms 10. The diverging 10 arms have lower attaching portions 19 which are riveted or otherwise secured to the outer faces of the side walls of the bucket or receptacle and the track is preferably supported at one or more points by posts 20 15 provided with horizontal arms 21 carrying an approximately L-shaped bracket 22 having an upwardly extending terminal supporting portion 23 provided with a forked upper end 24 to receive the track which may 20 be secured in the fork of the supporting bracket by any suitable means. The horizontal arm 21 which extends outwardly from the upper portion of the post 20 is preferably braced by a bar or member 25 arranged 25 at an inclination and extending upwardly from the post to the outer portion of the arm 21. Any number of the intermediate supports may be employed for maintaining the track 14 in substantially a horizontal position. 30

The hinged dumping bottom sections 4 are braced at free inner portions by transverse bars 26 having upwardly extending terminal portions 27 secured to the outer 35 faces of the sides or wings 7 and provided with terminal eyes 28 into which are linked branches 29 of chains 30 located at opposite sides of the bucket or receptacle and supported centrally of the upper portions of the 40 side walls 2 by suitable pulleys 31 and extending along the side walls from the pulleys 31 to one end of the bucket or receptacle and passing around corner pulleys 32 of a horizontal supporting bar or member 33. 45 The horizontal supporting bar or member 33 which is suitably secured to the contiguous end wall of the bucket or receptacle at the top thereof is provided at opposite sides of the center with pulleys 34 and the said 50 chains 30 are guided over the said pulleys 34 and extend downwardly to and are connected with a slidable sleeve or member 35.

Instead of employing chains the flexible connection 30 may be constructed of any 55 other suitable material such as flexible wire cables, ropes or the like and the side pulleys 31 are mounted in suitable brackets 36 preferably constructed of strap metal as shown but any other suitable material may of 60 course be employed for this purpose.

The corner pulleys 33 which are arranged horizontally are mounted in corner recesses 37 of the supporting bar or member 33 and the flexible connections are retained on the 65 pulleys 32 by a guard 38 consisting of metal-

lic straps and also forming bearings for the upper ends of the pivots or spindles 39 of the pulleys 32. The pulleys 34 are mounted in suitable brackets 40 and are located at opposite sides of a central recess 41 into 70 which extends the upper end of a vertical bar or member 42 which forms a guide for the slidable sleeve 35. The upper end 43 is reduced to form a tenon and is secured in a mortise 44 in the supporting bar or member 33 at the top of the central recess 41. The guide pulleys are preferably flanged as 75 shown and the flexible connections 30 move over the said pulleys when the slidable sleeve or member 35 travels upwardly and 80 downwardly along the guide bar or member 42. The vertical guide bar or member 42 is arranged in spaced relation with the adjacent end wall of the bucket or receptacle. The lower end of the vertical guide bar 42 85 which is provided with a recess 45 to receive an arm 46 of a catch 47 is mounted between brackets 48 and 49. The brackets are approximately L-shaped and are riveted or 90 otherwise secured to the adjacent end wall of the bucket or receptacle and the bracket 49 is provided at the top and bottom with projecting flanges 50, which fit against the guide bar 42 at the bottom thereof and also 95 at the top of the recess 45.

The catch 47 consists of an approximately vertical body portion and the said arm 46, which extends inwardly from the body portion at a point intermediate of the ends thereof; and the said arm 46 is pierced by a 100 horizontal pivot 51 which extends through the guide bar and the brackets 48 and 49. The upper end of the body portion of the catch is provided with a tooth 52 for engaging a recess 53 of the slidable sleeve 35 and the said catch which is maintained in engagement with the recess of the sleeve by a coiled spring 54 is connected at its upper end with one end of a rope 55 or other suitable flexible connection. The coiled spring 105 is interposed between the guide bar and the lower end of the catch for urging the upper end inwardly into engagement with the slid- 110 able sleeve 35. The recess 53 forms a shoulder to engage with the tooth 52 but any other form of shoulder may of course be provided. When the sleeve is moved downwardly on the guide bar the flexible connections 30 are caused to swing the dumping bottom sections to their closed positions and 115 when the catch is withdrawn from engagement with the sleeve the latter is released and permits the dumping bottom sections of the bucket or receptacle to swing downwardly under the influence of the contents 120 which are thereby discharged from the bucket or receptacle. The upward movement of the sleeve on the guide bar 42 is limited by a stop 56 carrying a cushioning device 57 which is adapted to absorb and 125 130

dissipate the jar incident to the stopping of the slideable sleeve. The stop 56 preferably consists of a relatively fixed sleeve or collar provided with a set screw 58 which is adapted to secure the collar 56 at different points along the guide bar to limit the opening movement of the dumping bottom section. By this construction the bottom section may be permitted to open completely for discharging the contents of the bucket or receptacle at one point or they may be partially opened to scatter the contents of the bucket or receptacle over the surface of the ground while the bucket or receptacle is traveling along the track.

The cushion 57 preferably consists of a coiled spring disposed on the guide bar 42 and secured at its upper end to the adjustable collar 56 but any other suitable form of cushion may of course be employed for this purpose.

The rope 55 extends from the catch 47 to a guide pulley 58 of the post or support 15 and then passes through the spaces between the diverging arms of the hangers of the bucket or receptacle and extends to a guide pulley 59 which is mounted on the other post or support 16. From this point the operating rope extends to the bucket or receptacle and is connected with the same by means of a screw 60 or other suitable fastening means mounted on the outer or front hanger. By this construction the operating rope is connected with the bucket or receptacle at the opposite ends thereof and it is adapted to be pulled upon to move the receptacle or bucket forwardly to the point where the contents thereof are to be dumped. The latch is then tripped to release the slideable sleeve and dumping sections of the bottom by pulling upon the end of the rope extending to the catch 47. After the contents of the bucket or receptacle have been discharged, the end of the rope which is connected with the catch is pulled upon to return the bucket or receptacle to the starting point. A single rope is adapted to serve as an operating or actuating rope and also as a trip rope for dumping the receptacle. The operator may stand at the post or support 15 and move the bucket or receptacle forwardly to the point of discharge, and the bucket or receptacle is located at an elevation sufficient to be out of the way of the stock. The contents of the bucket or receptacle may be discharged at one point or it may be scattered over the ground by limiting the opening movement of the dumping sections and moving the bucket or receptacle along while the contents are being discharged through a restricted opening or outlet. The slideable sleeve is provided with a suitable handle 61 by means of which the sleeve is moved downwardly to the lower portion of the guide bar 42 and the catch automatically engages the

sleeve to lock the hinged bottom or dumping sections in their closed position.

What is claimed is:—

1. A carrier of the class described including a receptacle having a dumping bottom, a vertically slideable member mounted on the receptacle, flexible connections extending from the said member to the dumping bottom, guiding means for the flexible connections, a catch arranged to engage the slideable member for locking the same against vertical movement, and a combined operating and trip rope secured at one end to the catch and connected at the other end with the receptacle and extending to points at opposite sides of the receptacle and adapted to be pulled in one direction to move the receptacle outward, and in the opposite direction to trip the catch and also to return the receptacle to its initial position.

2. A carrier of the class described including a bucket having hinged bottom sections, a vertically slideable member mounted on the bucket at one of the end walls thereof between the top and bottom of the same, flexible connections connecting the vertically slideable member with the bottom sections, guide pulleys for the flexible connections, a catch arranged to engage the slideable member for locking the same against movement and means for releasing the catch.

3. A carrier of the class described including a bucket having a dumping bottom, a vertical guide mounted on one of the walls of the bucket, a member slideable along the guide, flexible connections extending from the said member to the dumping bottom, guide pulleys for the flexible connections, a catch for holding the said member against movement, and means for limiting the movement of the said member.

4. A carrier of the class described including a receptacle having a dumping bottom, a vertical guide carried by the receptacle, a member slideable along the guide and connected with the dumping bottom, a catch for holding the said member against movement, and an adjustable stop having a cushion for limiting the movement of the said member.

5. A carrier of the class described including a bucket having a dumping bottom, a vertical guide bar mounted on the exterior of one of the end walls of the bucket, a sleeve slideable along the guide bar, flexible connections connecting the sleeve with the dumping bottom, guide pulleys for the flexible connections, and a catch for locking the sleeve against movement.

6. A carrier of the class described including a bucket provided with hinged bottom sections, a vertical guide mounted on the exterior of one of the walls of the bucket or receptacle, a sleeve slideable on the guide, flexible connections extending from the sleeve and having branches connected to the

- hinged bottom sections, means for guiding the flexible connections and a catch for locking the sleeve against movement.
7. A carrier of the class described including a bucket or receptacle provided with hinged bottom sections, a vertical guide mounted on the bucket or receptacle, a sleeve slideable on the guide, flexible connections extending from the sleeve and having branches connected to the hinged bottom sections, side pulleys located at opposite sides of the bucket or receptacle and receiving the flexible connections and corner and central pulleys located at one end of the bucket or receptacle and guiding the flexible connections to the said sleeve.
8. A carrier of the class described including a bucket or receptacle provided with bottom sections, at their outer ends, a supporting bar mounted on the bucket or receptacle at one end thereof and provided with central and corner pulleys, a vertical guide bar secured to the supporting bar and extending downwardly therefrom, brackets supporting the lower end of the guide bar, a sleeve slideable on the guide bar, guide pulleys mounted on the side walls of the bucket or receptacle and located above the inner end of the bottom sections, flexible connections connected to the said sleeves and arranged on the said pulleys and having branches connected to the bottom sections

of the bucket or receptacle and means for locking the sleeve against movement.

9. A carrier of the class described including a bucket or receptacle having bottom sections hinged at their outer ends, a vertical guide mounted on the bucket or receptacle at one end thereof, flexible connections extending from the bottom sections, a sleeve slideable along the guide and connected with the flexible connections, guiding means for the said flexible connections, and an adjustable stop having a cushioning device located in the path of the said sleeve.

10. A carrier of the class described including a bucket or receptacle having hinged bottom sections provided with wings, flexible connections provided with branches secured to the said wings and extending upwardly therefrom, guiding means carried by the bucket or receptacle for the said flexible connections, a slideable member guided on the receptacle and connected with the said flexible connections and means for holding the slideable member against movement and tripping the same.

In testimony whereof I affix my signature in presence of two witnesses.

LOUIS H. TREIBER.
